(57) **CLAIM**

The ornamental design for a computer mouse with scanner, as shown and described.

DESCRIPTION

FIG. 1 is a top perspective view of a computer mouse with scanner embodying our new design;

FIG. 2 is a bottom perspective view thereof. The larger middle rectangle illustrates a transparent member having an inner surface that is coated with a material to form a non-transparent frame between the larger middle rectangle and the smaller middle rectangle;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof. The larger middle rectangle illustrates a transparent member having an inner surface that is coated with a material to form a non-transparent frame between the larger middle rectangle and the smaller middle rectangle.

The broken lines illustrate environmental structure not forming part of the claimed design.
